UNITED STATES PATENT OFFICE.

EARL J. EARLY, OF PHILADELPHIA, PENNSYLVANIA.

COMBINATION DRAFTING APPLIANCE.

SPECIFICATION forming part of Letters Patent No. 777,407, dated December 13, 1904.

Application filed February 4, 1904. Serial No. 191,916. (No model.)

To all whom it may concern:

Be it known that I, EARL J. EARLY, a citizen of the United States, residing at Philadelphia, in the county of Philadelphia and State of Pennsylvania, have invented certain new and useful Improvements in Combination Drafting Appliances, of which the following is a specification.

This invention relates to an appliance for use in instrumental drawing, and is designed to combine in one instrument coöperative means for forming right lines, curves in connection therewith, either tangential or otherwise, as desired, angles of fifteen degrees, thirty degrees, forty-five degrees, sixty degrees, seventy-five degrees, and ninety degrees, together with guides for the correct formation of letters and numerals. For students, amateurs, or those of limited means and having limited use for instruments it will be of especial utility, as it will avoid the purchase and care of a multiplicity of instruments which have heretofore been necessary to use in doing that which can be done with this single instrument.

The invention is illustrated in the accompanying drawings, wherein similar parts are designated by similar characters of reference, in which—

30 Figure 1 is a view of one side of the instrument. Fig. 2 is a view of the opposite side of the instrument.

The general outline of the instrument is a triangle whose edges 1 2 3 form angles of forty-five degrees, sixty degrees, and seventy-five degrees at their junctions. In order to provide for the formation of other angles which with those enumerated are the most in use, the body has an aperture 4 vertical to edge 3, with lines 5 6 in continuation of its edges to edge 3, which, with edge 3, form angles of ninety degrees, while from the opposite end of aperture 4 the line 5 runs to the apex of the forty-five-degree angle and combined with edge 1 forms an angle of fifteen degrees, while line 6 from the opposite side of the aperture extends to edge 2 and in conjunction therewith forms an angle of thirty degrees. Thus it will be seen that by the coöperative use of edges 1 3, aperture 4, and its

lines 5 angles fifteen degrees, seventy-five degrees, and ninety degrees are formed, while by the coöperative use of edges 2 3, aperture 4, and its lines 6 angles of thirty degrees, sixty degrees, and ninety degrees, making in 55 one instrument a triangle of forty-five degrees, sixty degrees, seventy-five degrees, another of fifteen degrees, seventy-five degrees, ninety degrees, and another of thirty degrees, sixty degrees, ninety degrees.

The instrument has an aperture 7, whose edge is composed of a variety of curves which may be used singly for mixed curved lines or in conjunction with edges 1 2 3 or the edges of aperture 4 for the formation of mixed right 60 lines and curved lines either tangential or otherwise. The body of the triangle also has an aperture 8, whose edges 9 10 11 12 13 14 15 16 may form the combined lines for letters and numerals in broad formation, and aperture 17, 65 whose edges 18 19 20 21 22 23 24 25 may form the combined lines for letters and numerals in medium-breadth formation, an aperture 26, whose edges 27 28 29 30 31 32 33 34 may form the combined lines for letters and numerals in 70 narrow formation, so that by the combined and coöperative use of the various parts as set forth drawings with right lines, combined right and curved lines, angles, and the letters and numerals descriptive thereof may by this 75 single instrument be correctly formed.

I claim—

1. The combination in a drawing appliance, of a body of suitable material with edges which form angles of forty-five degrees, sixty degrees and seventy-five degrees; having an aperture through the body, vertical to one side, with one of its edges in direct alignment with the vertex of the forty-five-degree angle and forming with the adjacent edge of 85 the triangle an angle of fifteen degrees the opposite side of the opening with the triangle's adjacent edge forming an angle of 90 thirty degrees, and at its base each edge of the opening with the base edge of the triangle forming angles of ninety degrees the triangle also having an aperture formed of composite curved lines.

2. The combination in a drawing appliance of a body of suitable material with edges which 95

form three angles of different degrees; having an aperture through the body vertical to one of its edges, one edge of the aperture being in direct alinement with the vertex and 5 an opposite parallel edge of the aperture which with the adjacent edges of the triangle form acute angles of different degrees from those formed by the triangle's edges, and at its base with the adjacent edge of 10 the triangle forming two right angles; the body also having multiple apertures by which the horizontal together with vertical lines of letters and numerals, and lines of different degrees of angularity for the same, may be 15 drawn for their formation in broad, medium-breadth or narrow designs.

3. The combination in a drawing appliance of a body of suitable material with edges which 20 form three angles of different degrees, having an aperture vertical to one edge, one of

its edges being in direct alinement with the vertex where the edges of the aperture and the triangle's adjacent edges form acute angles of different degrees from those formed by the triangle's edges and at the base of the 25 aperture with the edge of the triangle as a base form right angles; also having an aperture whose edges form composite curved lines; also having multiple apertures by which the horizontal and vertical lines of letters and 30 numerals, and lines of different degrees of angularity for the same may be drawn for their formation in broad, medium-breadth and narrow designs.

In testimony whereof I affix my signature in 35 presence of two witnesses.

EARL J. EARLY.
